UNITED STATES PATENT OFFICE.

ALBERT Y. THORNTON AND ARTHUR L. MUNROE, OF JOHNSTON, RHODE ISLAND.

DEVICE FOR PLUGGING SPRINKLER-HEADS.

No. 884,430.

Specification of Letters Patent. Patented April 14, 1908.

Application filed November 21, 1907. Serial No. 408,218.

To all whom it may concern:

Be it known that we, ALBERT Y. THORNTON and ARTHUR L. MUNROE, citizens of the United States, residing at Johnston, in the county of Providence, State of Rhode Island, have invented a new and useful Device for Plugging Sprinkler-Heads, of which the following is a specification.

This invention relates to a device for plugging sprinkler-heads of that class that are arranged within a building and are adapted automatically to discharge a spray of water in case of fire in an apartment or room where they are located.

The invention is intended primarily, to provide a novel and efficient means for closing or plugging a sprinkler-head should its valve accidentally be dislodged, thereby permitting the water to escape to the detriment of the building or of any goods within its effective area.

As sprinkler-heads of this character are generally supplied with water from a common source, it is not possible to cut off the supply from a single head in case its valve becomes accidentally displaced and owing to this fact considerable damage frequently arises from the escape of water accompanying such accident.

The object of the present invention is to provide, as a new article of manufacture, an attachment for application to sprinkler-heads which shall be effective in promptly plugging the escape orifices in the sprinkler-head, and further to adapt such attachment automatically to be released in case of fire, whereby the sprinkler will be as effective as though it had the ordinary valve and its fixtures applied thereto.

With the above and other objects in view as will appear as the nature of the invention is better understood, the same consists in the novel construction and combination of parts of a closure or plug for sprinkler heads, as will be hereinafter fully described and claimed.

In the accompanying drawings, forming a part of this specification, and in which like characters of reference indicate corresponding parts: Figure 1 is a view in side elevation, displaying a sprinkler-head equipped with the closure or plug of the present invention. Fig. 2 is a view in vertical longitudinal section. Fig. 3 is a fragmentary sectional detail view in elevation of a portion of the attachment. Fig. 4 is a perspective detail

view of the closure. Fig. 5 is a fragmentary detail view of a portion of the closure. Fig. 6 is a view in side elevation of the plug member of the closure. Fig. 7 is a sectional detail view of a part of the device.

Referring to the drawings, 1 designates the valve casing of the sprinkler-head, which, as usual, is provided with a threaded connection by which it is connected with a suitable water supply pipe. The casing houses a diaphragm valve seat 3, of the usual construction, and which, as will be well understood, is adapted slightly to be flexed by the closure or plug when the same is assembled therewith, thus to secure a water-tight joint. Depending from the rim 4 of the diaphragm are arms 5 which have arranged at their lower ends a seat 6, such as is common with structures of this character.

The feature of novelty of the present invention resides in the closure which is shown in detail in Fig. 4. This closure embodies a handle or lever 7, one end of which is enlarged and is provided with a relatively broad cam surface 8 that is adapted to engage with the seat 7, and adjacent to one terminal of the cam with a stop or abutment 9 that will operate to limit the movements of the lever, in one direction, relatively to the seat. Opposite the cam there is provided a seat 10, the end wall 11 of which is inclined transversely of the length of the handle and is designed to be engaged by the beveled terminal 12 of the shank 13 of the plug 14, this latter being hemispherical in contour in order to engage with the orifice of the diaphragm. The shank is held within the seat by solder designated by 15, and this, as will be apparent, will fuse under the action of heat, thereby permitting the shank to become disconnected and escape laterally from connection with the handle and thus allow the water to escape through the orifice in the diaphragm. This latter feature is one of great importance, inasmuch as, if the sprinkler-head is provided with this emergency closure, and a fire should occur that would prevent an attendant from releasing the plug, it will of its own accord, owing to the fusible connection of the shank 13 therewith, become disconnected from the sprinkler-head and thus allow the water to escape.

As an additional feature of novelty, means is provided by which the plug may be attached to or detached from a sprinkler head without the employment of a ladder, where-

by not only is the manipulation of the device facilitated, but the loss by fire and damage by water that frequently results, owing to the loss of time required to find and arrange a ladder in proper place to permit the positioning or removal of the plug, are obviated. This means consists of a pole or handle 16 of any desired length, one end of which carries a head or casting 17 provided with a transversely disposed seat or orifice 18 that is rectangular in cross section and is longitudinally tapered to receive the similarly shaped terminal 19 of the lever 7, the latter being provided with a shoulder or stop 20 to limit its insertion within the seat. In positioning a plug, it will only be necessary to dispose the terminal 19 of the lever within the seat 18, insert the plug 14 in the valve seat 3, and then draw down upon the pole, whereupon the cam surface 8 will ride upon the seat 6 and thereby close the discharge opening. The reverse of this procedure is observed when the plug is to be removed, whereas under such contingency the pole is merely pushed upward.

The improvements herein defined, while simple in character, will be found thoroughly efficient for the purposes designed and will result in a large saving to merchants from loss of goods by a fire and water.

Having thus fully described the invention what is claimed is:—

1. As a new article of manufacture, a closure for sprinkler-heads embodying a handle having a seat, the end wall of which is beveled transversely to the length of the handle, and a plug provided with a shank fusibly held within the seat and having its end beveled to engage the said wall. 35

2. As a new article of manufacture, a closure for sprinkler-heads embodying a handle having a cam on one side thereof and a seat opposite the cam, and a plug having a shank fusibly held within the seat. 40

3. As a new article of manufacture, a closure for sprinkler heads embodying a handle having a cam on one side thereof that projects laterally beyond the handle and a seat opposite the cam and a plug having a shank fusibly held within the seat. 45 50

In testimony that we claim the foregoing as our own, we have hereto affixed our signatures in the presence of two witnesses.

ALBERT Y. THORNTON.
ARTHUR L. MUNROE.
